CLAIM

The ornamental design for an orthopedic woven retention device, as shown and described.

DESCRIPTION

FIG. 1 is a perspective view of a first embodiment of an orthopedic woven retention device of the claimed design; FIG. 2 is a front elevational view thereof; FIG. 3 is a rear elevational view thereof; FIG. 4 is a right side elevational view thereof; FIG. 5 is a left side elevational view thereof; FIG. 6 is a bottom plan elevational view thereof; FIG. 7 is a top plan elevational view thereof; FIG. 8 is a perspective view of a second embodiment of an orthopedic woven retention device of the claimed design; FIG. 9 is a front elevational view thereof; FIG. 10 is a rear elevational view thereof; FIG. 11 is a right side elevational view thereof; FIG. 12 is a left side elevational view thereof; FIG. 13 is a bottom plan elevational view thereof; and, FIG. 14 is a top plan elevational view thereof.

The features shown in broken lines have been shown for the purpose of illustrating portions of the orthopedic woven retention device that form no part of the claimed design.
